HEADBOX FOR PAPER MAKING MACHINE
Fred J. Gedemer, Appleton, Wis., assignor to Allis-Chalmers Manufacturing Company, Milwaukee, Wis.
Filed Dec. 14, 1964, Ser. No. 418,154
7 Claims. (Cl. 162—347)

This invention relates to paper making machines and in particular a headbox providing control of paper web formation on such as a Fourdrinier wire in a manner that provides particularly advantageous control for making light and tissue weight paper.

In forming light weight paper on a Fourdrinier paper machine it is necessary that the headbox deposit paper stock on the Fourdrinier wire with a spouting velocity that is at nearly as possible equal to the speed of the wire. In order to achieve such stock velocity with a high speed wire, the headbox maintains a pressure on the stock. To reduce a possibility to such a high velocity stream being deposited on the wire with turbulence that could cause the stream to be of somewhat uneven thickness, the stream is discharged over a lower lip and beneath an upper lip that projects farther downstream than the lower lip, to cover the initial web forming area. This initial web forming area beneath the projecting upper lip may be at least partly over wire still on the farthest upstream supporting roll, called the breast roll. With such an arrangement the breast roll may be of a type having peripheral opening for receiving water passing through the wire before it leaves the breast roll. Internal suction boxes may also be provided within such a breast roll to collect such water within the roll and to drain away such collected water.

Such headboxes have often included rigid plate structures carefully and critically designed to achieve a suitable smooth surface of accurate curvature to conform to the desired drainage profile over the breast roll. Usually adjusting linkages are associated with the enclosure so that the dimensions of the forming zone may be varied somewhat depending on the type of stock being used. These adjusting linkages are usually fairly complex and massive because it is essential to provide highly accurate positioning of the headbox sections defining the drainage profile so as to avoid undesirable interference with the smooth flow of the stock stream and even deposit of the fiber in the web forming area.

It is an object of the present invention to provide a new and improved adjustable drainage defining profile for a headbox that will deposit stock upon a rapidly moving wire and achieve precise control of web formation on a Fourdrinier wire.

It is another object of the present invention to provide a new and improved adjustable drainage defining profile for a headbox, with adjusting linkages preloaded so there will be no relative movement between links as a result of slightly loose fits arising from practical limitations on the degree of manufacturing tolerances that can be achieved.

It is also an object of the present invention to provide for an initial adjustment of the vertical spacing over the wire of the outer edge of the upper lip of the headbox outlet and an additional adjustment for the throat of the headbox outlet without moving the initial position of that edge of the upper lip.

According to a preferred embodiment of the present invention, a pressure headbox is provided with a stock reservoir having a movable front wall assembly with a lower portion extending forward of the top of the reservoir to define a forwardly extending upper lip of a stock outlet opening projecting over a portion of a forming wire on a breast roll. The forward edge of the upper lip may be located over the turning axis of the breast roll where the wire begins its horizontal reach off the breast roll.

2

A vertical support wall extends forward of the top portion of the headbox reservoir and upwardly of the upper lip of the stock outlet. A pantographic linkage assembly is connected to the vertical support wall with the links defining a plane parallel to the vertical plane of the support wall. The pantographic linkage assembly has three vertical links and a pair of vertically spaced parallel links transverse to the vertical links. The links are pivotally connected together at each intersection. The forward ends of the transverse links extend forward of the support wall where they are pivotally connected at vertically spaced locations on the forwardmost vertical link. The rearward ends of the transverse links are pivotally connected to vertically spaced locations on the rearmost vertical link and to the support wall near the rear of the support wall. The vertical link intermediate the forward and rear vertical links is pivotally connected to the transverse links and the support wall near the front vertical edge of the support wall. The intermediate and rearward vertical links extend downwardly to a location below the lower transverse link to locations spaced above the forwardly projecting upper lip of the stock outlet where these ends are pivotally connected to the support wall.

A first lifting device is connected to the top of the forwardmost vertical link, which is arranged over the forward edge of the upper lip. This lifting device is operative to pivot the forward end of the support wall about the lowest pivotal connection on the rear link and accordingly lift or lower the forward edge of the upper lip to provide an initial adjustment of the clearance of the upper lip of the stock outlet over the wire where the wire begins its horizontal reach off the breast roll. A second lifting device is pivotally connected to the top of the rear link. After the first lifting means is operated to establish a desired clearance of the upper lip over the wire, the throat profile of the outlet to the rear of the forward edge of the upper lip can be adjusted without changing the established clearance of this edge over the wire. This can be accomplished by operating the second lifting device to pivot the rear end of the support wall and the upper lip about the forward edge of the upper lip which is established as the pivotal axis for such movement with the described linkage. Certain arrangements according to the prior art provide for lifting a rear portion of an upper lip of a stock outlet but without establishing a pivotal axis coincident with the forward edge of the upper lip. Therefore, when such prior art arrangements are operated in that manner, each adjustment of the throat profile changes the clearance over the wire. Operators have had the experience with such prior art arrangements of unintentionally lowering the forward edge of the upper lip on the rapidly moving Fourdrinier wire and chopping through the wire. Therefore, it is an important advantage of the present invention that the Fourdrinier wire cannot be cut when adjusting the rear portion of the upper lip to change the profile of the throat of the stock outlet.

To provide for very accurate adjustment of the front wall assembly of the headbox, all of the pivotal connections referred to are preloaded to eliminate uncontrolled movement as a result of small but unavoidable clearances in the pivotal connections. This is accomplished by a third lifting device pivotally connected to the support wall above the upper transverse link and between the intermediate and rear vertical links. Sufficient lifting force is applied by this third lifting device to place all connections in the described pantographic assembly under load. Operation of the assembly of the present invention therefore never applies a force to an unloaded connection and all parts are always in their fully loaded positions within clearances ready to move under precise control without

any need to first move to take up slack in loose connections.

Other objects and advantages of the present invention will appear from the following more detailed description with reference to the accompanying drawing which shows a partly sectional vertical view of a headbox according to the present invention.

The movable front wall assembly 17 is provided with upper portions 22 and portions 23 extending forward of the portions 22 terminating with a forwardly extending upper lip 24 over stock outlet opening 19. The upper lip 24 projects over a portion of forming wire 10 on breast roll 11. The forward edge 25 of the upper lip 24 may be located over the turning axis of the breast roll where the wire 10 begins its horizontal reach off the breast roll 11. A vertical support wall 30 extends forward of the top wall portion 22 and upwardly of the lower wall portions 23 and upper lip 24 of the stock outlet 19. A pantographic linkage assembly 31 is connected to the vertical support wall 30 with links defining a plane parallel to the vertical plane of the support wall 30. The pantographic linkage assembly 31 has three vertical links 32, 33, 34 and a pair of vertically spaced parallel links 35, 36 transverse to the vertical links 32-34. The links 32-36 are pivotally connected together at each intersection by connecting shafts 37-42. The forward ends of the transverse links 35, 36 extend forward of the support wall 30 where they are pivotally connected by shafts 37, 38 to vertically spaced locations on the forwardmost vertical link 32. The rearward ends of the transverse links 35, 36 are pivotally connected by shafts 41, 42 to vertically spaced locations on the rearmost vertical link 34. The vertical link 33 intermediate the forward and rear vertical links 32, 34 is pivotally connected by shafts 39, 40 to the transverse links 35, 36. The intermediate link 33 and rearward vertical link 34 extend downwardly below the lower transverse link 36 to locations where these ends are pivotally connected by shafts 43, 44 to the support wall 30 and define a plane X-X coincident with edge 25 and parallel to links 35, 36.

A first lifting device 48 is pivotally connected by a shaft 49 to the top of the forwardmost vertical link 32 which is arranged over the forward edge 25 of the upper lip 24 to establish the edge 25 as the axis about which wall 30 pivots when adjusted by means that will hereinafter be described. The device 48 includes a depending rod 50 connected to a power shaft 51 by any suitable arrangement such as, for example, a rack and pinion assembly (not shown).

A second lifting device 54 is pivotally connected by a shaft 55 to the top of the rear link 34. The device 54 includes a depending rod 56 connected to a power shaft 57 which may also be by any suitable arrangement such as, for example, a rack and pinion assembly (not shown).

A third lifting device 60 for preloading all connecting shafts 37-44 of the pantographic linkage assembly 31, has a rod 61 pivotally connected by a shaft 62 to the support wall 30. The upper end of rod 61 projects through a floor plate 63 which is fastened to wall members 64 pivotally connected to a support bracket 65 by a shaft 66. A piston 67 is fastened to the top of rod 61 above the floor plate 63. One or more annular expandable air bags 68 may be arranged around the rod 61 and in the space between the floor plate 63 and piston 67. The lifting devices 48, 54, 60 are each mounted on brackets 70, 71, 72, respectively, which are in turn carried by support structure 73.

The top edge 74 of the upper wall portion 22 is beveled to slope upwardly in the direction toward the support wall 30. This edge 74 engages a pivotal bracket 75 and the edge 74 can slide on pivotal bracket 75 to maintain a closed connection with top wall 16 as the front wall assembly 17 is moved during operation such as will now be described. Joints between the front wall assembly 17, the side walls 14 and bottom wall 15 may be sealed in any

conventional manner, for example, by flexible seals or packing (not shown).

In the operation of the described apparatus, air bag 68 is filled with air pressure to push upwardly upon piston 67 and lift rod 61 and support wall 30 to preload the pivotal connections of the linkage assembly 31 at shafts 37-44. The clearance of lip 24 and edge 25 over wire 10 is adjusted when power shaft 51 of the lifting device 48 raises rod 50 to pivot the forward end of the support wall 30 about the lowest pivotal connection at shaft 44 on the rear link 34. This movement may be applied to provide an initial adjustment of the clearance of the upper lip 24 of stock outlet 19 over the wire 10 where the wire begins its horizontal reach off breast roll 11.

After the first lifting device 48 is operated to establish a desired clearance of the upper lip 24 over the wire 10, the throat profile of the stock outlet 19 to the rear of the forward edge 25 of the upper lip 24, can be adjusted without changing the established clearance of this edge 24 over the wire 10. This can be accomplished by operating the second lifting device 54 to raise or lower shaft 56 and link 34 to pivot the rear end of the support wall 30 and the upper lip 24 about the forward edge 25 of the upper lip 24 which is established as the pivotal axis for such movement with the described linkage 31. Because the pivotal axis for such movement is the edge 25, an operator can devote full attention to adjusting the profile of stock outlet 19 without concern about inadvertently chopping wire 10 with edge 25. Furthermore, because all connections at the shafts 37-44 are preloaded, precise control is achieved for accurate adjustment of the elevation of edge 25 over wire 10 and the profile of outlet 19 rearward of edge 25.

From the foregoing it will be understood that the present invention is possessed of unique advantages. However, such modifications and equivalents of the disclosed concepts such as readily occur to those skilled in the art are intended to be included within the scope of this invention and thus the scope of this invention is intended to be limited only by the scope of the claims such as are, or may hereafter be, appended hereto.

The embodiments of the invention in which an exclusive property or privilege is claimed are defined as follows:

1. In a paper machine having a looped forming wire, a stock flow distributing headbox comprising a bottom wall extending laterally of said wire with a stock discharging lower lip, and an adjustable front wall assembly having wall structures including an upper portion and a lower portion projecting forward of said upper portion with an upper lip having a leading edge in close proximity to a portion of said wire and above said lower lip to define therebetween a stock outlet opening, means for adjusting said front wall assembly comprising: a vertical support wall connected to said wall structures extending forward of said upper portion and upwardly of said lower portion and said upper lip; a pantographic linkage assembly defining a plane parallel to said support wall, said linkage having a forward vertical link forward of said support wall and directly above said leading edge, a rear vertical link in close proximity to the rear of said support wall, an intermediate vertical link in close proximity to the front of said support wall, a pair of vertically spaced parallel links transverse to said vertical links and pivotally connected thereto at each intersection therewith, said intermediate and said rear vertical links having extensions downwardly of the bottom one of said transverse links, and a shaft through each said extension pivotally connecting the lower end of said intermediate and rear links to said support wall at locations where the central axis of each said shaft defines a plane coincident with said leading edge; and a lifting device connected to said rear link for adjusting the profile of said stock outlet by pivoting said front wall assembly about a substantially fixed

lateral axis substantially coincident with said leading edge.

2. In a paper machine having a looped forming wire, a stock flow distributing headbox comprising a bottom wall extending laterally of said wire with a stock discharging lower lip, and an adjustable front wall assembly having wall structures including an upper portion and a lower portion projecting forward of said upper portion with an upper lip having a leading edge in close proximity to a portion of said wire and above said lower lip to define therebetween a stock outlet opening, means for adjusting said front wall assembly comprising: a vertical support wall connected to said wall structures extending forward of said upper portion and upwardly of said lower portion and said upper lip; a pantographic linkage assembly defining a plane parallel to said support wall, said linkage having a forward vertical link forward of said support wall and directly above said leading edge, a rear vertical link in close proximity to the rear of said support wall, an intermediate vertical link in close proximity to the front of said support wall, a pair of vertically spaced parallel links transverse to said vertical links and pivotally connected thereto at each intersection therewith, said intermediate and said rear vertical links having extensions downwardly of the bottom one of said transverse links, and a shaft through each said extension pivotally connecting the lower end of said intermediate and rear links to said support wall at locations where the central axis of each said shaft defines a plane coincident with said leading edge; a first lifting device connected to said forward link for setting clearance of said edge over said wire; and a second lifting device connected to said rear link for adjusting the profile of said stock outlet by pivoting said front wall assembly about a substantially fixed lateral axis substantially coincident with said leading edge.

3. In a paper machine having a looped forming wire, a stock flow distributing headbox comprising a bottom wall extending laterally of said wire with a stock discharging lower lip, and an adjustable front wall assembly having wall structures including an upper portion and a lower portion projecting forward of said upper portion with an upper lip having a leading edge in close proximity to a portion of said wire and above said lower lip to define therebetween a stock outlet opening, means for adjusting said front wall assembly comprising: a vertical support wall connected to said wall structures extending forward of said upper portion and upwardly of said lower portion and said upper lip; a pantographic linkage assembly defining a plane parallel to said support wall, said linkage having a forward vertical link forward of said support wall and directly above said leading edge, a rear vertical link in close proximity to the rear of said support wall, an intermediate vertical link in close proximity to the front of said support wall, a pair of vertically spaced parallel links transverse to said vertical links and pivotally connected thereto at each intersection therewith, said intermediate and said rear vertical links having extensions downwardly of the bottom one of said transverse links, and a shaft through each said extension pivotally connecting the lower end of said intermediate and rear links to said support wall at locations where the central axis of each said shaft defines a plane coincident with said leading edge; a first lifting device connected to said forward link for setting clearance of said edge over said wire; a second lifting device connected to said rear link for adjusting the profile of said stock outlet by pivoting said front wall assembly about a substantially fixed lateral axis substantially coincident with said leading edge; and a third lifting device pivotally connected to the top of said support wall and operative to apply a lifting force to said support wall to apply and maintain load upon said pivotal connections.

4. In a paper machine having a forming wire looped around a breast roll, a stock flow distributing headbox comprising a bottom wall extending laterally of said wire with a stock discharging lower lip in close proximity to a portion of said wire on an upwardly turning portion

of said breast roll below the top of said breast roll, and an adjustable front wall assembly having wall structures including an upper portion and a lower portion projecting forward of said upper portion with an upper lip having a leading edge in close proximity to a portion of said wire forward and above said lower lip to define therebetween a stock outlet opening, means for adjusting said front wall assembly comprising: a vertical support wall connected to said wall structures extending forward of said upper portion and upwardly of said lower portion and said upper lip; a pantographic linkage assembly defining a plane parallel to said support wall, said linkage having a forward vertical link forward of said support wall and directly above said leading edge, a rear vertical link in close proximity to the rear of said support wall, an intermediate vertical link in close proximity to the front of said support wall, a pair of vertically spaced parallel links transverse to said vertical links and pivotally connected thereto at each intersection therewith, said intermediate and said rear vertical links having extensions downwardly of the bottom one of said transverse links, and a shaft through each said extension pivotally connecting the lower end of said intermediate and rear links to said support wall at locations where the central axis of each said shaft defines a plane coincident with said leading edge; and a second lifting device connected to said rear link for adjusting the profile of said stock outlet by pivoting said front wall assembly about a substantially fixed lateral axis substantially coincident with said leading edge.

5. In a paper machine having a looped forming wire looped around a breast roll, a stock flow distributing headbox comprising a bottom wall extending laterally of said wire with a stock discharging lower lip in close proximity to a portion of said wire on an upwardly turning portion of said breast roll below the top of said breast roll, and an adjustable front wall assembly having wall structures including an upper portion and a lower portion projecting forward of said upper portion with an upper lip having a leading edge in close proximity to a portion of said wire forward and above said lower lip to define therebetween a stock outlet opening, means for adjusting said front wall assembly comprising: a vertical support wall connected to said wall structures extending forward of said upper portion and upwardly of said lower portion and said upper lip; a pantographic linkage assembly defining a plane parallel to said support wall, said linkage having a forward vertical link forward of said support wall and directly above said leading edge, a rear vertical link in close proximity to the rear of said support wall, an intermediate vertical link in close proximity to the front of said support wall, a pair of vertically spaced parallel links transverse to said vertical links and pivotally connected thereto at each intersection therewith, said intermediate and said rear vertical links having extensions downwardly of the bottom one of said transverse links, and a shaft through each said extension pivotally connecting the lower end of said intermediate and rear links to said support wall at locations where the central axis of each said shaft defines a plane coincident with said leading edge; and a second lifting device connected to said rear link for adjusting the profile of said stock outlet by pivoting said front wall assembly about a substantially fixed lateral axis substantially coincident with said leading edge.

6. A stock flow distributing headbox having structures in fixed locations, and an adjustable front wall assembly having wall structures including an upper portion and a lower portion projecting forward of said upper portion with an upper lip having a leading edge to define therebeneath a stock outlet opening, means for adjusting said

front wall assembly comprising: a vertical support wall connected to said wall structures extending forward of said upper portion and upwardly of said lower portion and said upper lip; a pantographic linkage assembly connected to said fixed structure and said support wall and defining a plane parallel to said support wall, said linkage having a forward portion directly above said leading edge and a portion rearward of said forward portion connected to said support wall, a first lifting device connected to said forward portion for setting the vertical position of said edge relative to said fixed structure; a second lifting device connected to said rearward portion for adjusting the profile of said stock outlet by operating said pantographic linkage to pivot said front wall assembly about a substantially fixed lateral axis substantially coincident with said leading edge.

7. A stock flow distributing headbox having structures in fixed locations including a bottom wall extending laterally thereof with a stock discharging lower lip, and an adjustable front wall assembly having wall structures including an upper portion and a lower portion projecting forward of said upper portion with an upper lip having a leading edge above said lower lip to define therebetween a stock outlet opening, means for adjusting said front wall assembly comprising: a vertical support wall connected to said wall structures extending forward of said upper portion and upwardly of said lower portion and

8
said upper lip; a pantographic linkage assembly connected to said fixed structures and said support wall defining a plane parallel to said support wall, said linkage having a forward portion directly above said leading edge, and a portion rearward of said forward portion pivotally connected to said support wall, a first lifting device connected to said forward portion for setting clearance of said edge over said lower lip; a second lifting device connected to said rearward portion for adjusting the profile of said stock outlet by operating said pantographic linkage to pivot said front wall assembly about a substantially fixed lateral axis substantially coincident with said leading edge; and a third lifting device pivotally connected to the top of said support wall and operative to apply a lifting force to said support wall to apply and maintain load upon said pivotal connections.
